HIGH-PRESSURE PUMP

Lester V. Jones, Fort Worth, Tex., assignor of
one-fourth to John D. Dalton, Fort Worth, Tex.

Application February 16, 1948, Serial No. 8,619

1 Claim. (Cl. 103—129)

1

This invention relates to pumping apparatus for moving fluids, such as oil, water and the like, and it has particular reference to a low-speed, high-pressure pump capable of economically producing a continuous flow of fluids, and its principal object resides in the provision of a simple and inexpensive structure which can be adapted to almost any type of pumping operation according to its dimensions and adaptations.

An object of the invention is that of providing a pump of the rotary type having a plurality of paired wings or vanes operating in a cylindrical chamber in alternate movements whereby liquids can be moved rapidly and under relatively high pressures while the pump is operated at relatively low speeds.

Broadly, the invention contemplates the provision of a pump mechanism embodying a novel arrangement of a pair of opposed rotors, each having a pair of opposingly arranged vanes integrally formed thereon capable of functioning intermittently to move liquids through the apparatus.

While the foregoing objects are paramount, other and lesser objects will become manifest as the description proceeds, taken in connection with the appended drawings wherein:

Figure 1 is a vertical cross-sectional view of the invention, taken on lines 1—1 of Figure 2, showing the association of the rotor members and illustrating the intake passages in dotted lines centrally of the device.

Figure 2 is a transverse sectional view of the invention, taken on line 2—2 of Figure 1, showing the arrangement of gears in plan.

Figure 3 is a plan view of the invention.

Figure 4 is another vertical cross-sectional illustration, taken transversely of the section shown in Figure 1 on line 4—4 of Figure 2, and showing the outlet passages in dotted lines centrally of the invention.

Figure 5 illustrates the invention in partial section, on lines 5—5 of Figure 8, showing the rotors and motor in elevation and illustrating one pair of the tensioned stop members.

Figure 6 is a fragmentary partial cross-sectional view of the invention, taken on lines 6—6 of Figure 8, showing one of the opposite pairs of stops, the same being compressed.

Figure 7 is a plan view of the internal parts of the invention, the top being removed to illustrate the relative positions of the cams and stops, as well as the gears operating the rotors.

Figure 8 is a transverse cross-sectional view, taken on lines 8—8 of Figure 5, showing the ar-

2

angement of bearings between the rotors and illustrating the relative positions of the vanes, one pair of which is shown in dotted lines.

Figure 9 is a lateral sectional view through one of the rotors showing one of critical positions of the paired vanes with respect to the inlet and discharge passages.

Figure 10 illustrates, in another lateral sectional view through one of the rotors, the opposite critical positions of the paired vanes with respect to the inlet and discharge passages.

Figure 11 is a perspective illustration of the upper rotor member showing the opposingly arranged recesses in the peripheral gears.

Figure 12 is a perspective view of the lower rotor member showing the bearing race, cams and stop lugs common to both rotors.

Figure 13 is a perspective illustration of the internal sealing band for closing the space between the joined rotors.

Figure 14 is a perspective view of the external sealing band arranged opposite to the internal band.

Figure 15 is a transverse sectional view of one of the vanes showing the arrangement of the sealing bars fitted in grooves formed longitudinally of each edge, and

Figure 16 is a perspective view of one of the sealing members fitted in the vanes.

Accordingly, the invention comprises a casing 10, preferably cylindrical in form, and having legs 11 by which the assembly can be anchored in operative position. A circular cover plate 12 is provided for the casing 10 and is secured thereto by screws 13 arranged about its periphery, as shown in Figures 1, 2 and 4. A gasket 14 provides a suitable seal between the casing 10 and the cover 12 rendering the casing fluid-tight.

A vertical shaft 15 is rigidly arranged concentrically of the casing 10, its lower end being seated in a boss 16 formed in the bottom 17 of the casing 10 while the upper end is slightly tapered and extends into another boss 18 formed centrally of the cover 12. This arrangement is shown in Figures 1 and 4. Intake fluid passages 19 are formed longitudinally of the shaft 15 and are shown in dotted lines in Figure 1. Discharge passages 20 are formed in the shaft 15 parallel to the inlet passages 19 and these are shown in dotted lines in Figure 4. The passages 19 and 20 are also shown in Figures 8, 9 and 10 and their functions will presently become manifest.

A pair of rotors 21 and 22 are opposingly arranged in the casing 10 and rotatably supported on the shaft 15. The members 21 and 22 are

identically formed, as shown in perspective in Figures 11 and 12, each being cylindrical and having one of their ends 23 and 24 closed. Integral with each of the closures 23 and 24 is a pair of opposingly arranged wings or vanes 25 and 26 which are substantially wedge-shaped in transverse section, as shown in Figures 8 to 12 and 15.

Each pair of the vanes 25 and 26 is arranged parallel to the axis of the rotors 21 and 22 and is spaced to engage the shaft 15 on each side, in the manner shown in Figures 8, 9 and 10. As apparent in Figures 11 and 12 the paired vanes 25 and 26 are arranged opposite, the vanes 25 on the upper rotor 21 extending into the opposite rotor 22 while the lower set of vanes 26 on the latter extend into the rotor 21.

Formed about the peripheries of the closures 23 and 24 of the rotors 21 and 22 are sets of gear teeth 27 and 28 respectively. The teeth 27 on the rotor 21 are divided into paired segments by notches 29 and 30 while the teeth 28 are separated into segments by notches 31 and 32. These arrangements are shown in Figures 7, 11 and 12 and their functions will be described presently.

The rotors 21 and 22 are formed with swaged portions 33 and 34 which space the teeth 27 and 28 on the rotors from their opposite ends which are approximately the same in diameter as the arrangements of teeth 27 and 28. The open ends of the rotors 21 and 22 are formed with circular grooves 35 and 36 providing, when the members 21 and 22 are joined as in Figures 1, 4 and 5, a race for a plurality of roller bearings 37 affording a non-friction association between these members. It is entirely practical to form the rotors 21 and 22 without swaging the sides, thus the sides can be straight.

About the rims of the open ends of the rotors 21 and 22 are formed recesses 38 and 39 which provide shallow grooves when the rotors are joined to accommodate a band 40, shown in detail in Figure 14, to aid in sealing the chamber 41 defined by the joined rotors 21 and 22, as shown in Figures 1, 4, 5 and 6. Similar recesses 42 and 43 are formed internally of the open ends of the members 21 and 22 which, when joined, define a shallow groove 44 inside of the connected rotors to receive an expansion band 45, shown in Figure 13, sealing the joint within the chamber 41 opposite the band 40. Thus the chamber 41 is fluid-tight although capable of being independently rotated with respect to each other, the bands 40 and 45 being arranged to permit the free rotation of the rotors 21 and 22.

When the rotors 21 and 22 are operatively associated in the manner just described, and illustrated in Figures 1, 4, 5 and 6, the vanes 25 and 26 bisect the chamber 41, as in Figures 9 and 10, and operate intermittently as each rotor is turned a partial revolution, as will presently become apparent, to positions depicted in Figure 8 in solid and dotted lines.

In their assembled operative positions, as shown in Figures 1, 4, 5 and 7, the teeth 27 and 28 are arranged on the upper and lower ends of the assembly. The upper teeth 27 on the rotor 21 are engaged by oppositely arranged paired pinions 46 and 47 on shafts 48 and 49 on whose upper ends are gears 50 and 51 meshed on opposite sides of a gear 52 on the lower end of the shaft 53 of a motor 54 supported by brackets 55 on top of the casing 10, as in Figures 1 and 5.

The lower arrangement of teeth 28, on the rotor 22 are meshed with oppositely arranged pin-

ions 56 and 57 on shafts 58 and 59 on whose upper ends are gears 60 and 61 meshing on opposite sides of the gear 52 in transverse arrangement of the gears 50 and 51. The gear arrangement is illustrated in Figure 2 which shows the association of all of the gears 50, 51, 52, 60 and 61 and the directions of their rotation are indicated by arrows.

Each of the shafts 48, 49, 58 and 59 are journaled at their upper ends in bearings 62 in the cover plate 12 and suitable packing rings 63 are provided to prevent fluid passage thereby. The lower ends of the shafts 48, 49, 58 and 59 are supported in bosses 64 formed integral with the bottom 17 of the casing 10, as shown in Figures 1 and 4, in which non-friction bearings may be provided if desired. The assembled rotors 21 and 22 are journaled upon the shaft 15 and rotate about this member, upper and lower hardened sleeves 64' providing suitable bearings therefor.

The surface engaging edges as well as the outer ends of the vanes 25 and 26 have grooves 65 formed therealong to receive sealing bars 66 which may be in a single U-shaped unit, as illustrated in Figure 16, or may be, if considered more desirable, provided in sections of suitable length to be arranged in the grooves 65. A more suitable arrangement may be that of providing a plurality of bars of different lengths for each section.

The bars 66 are preferably hardened and are therefore wear-resistant as well as being capable of providing a more desirable seal between the engaging surfaces than would be afforded by the vanes themselves. It will be noted that the bars 66 are arranged to engage the inner surface of the chamber 41 the inner surfaces of the opposing closed ends 23 and 24 of the rotors 21 and 22, and the surface of the shaft 15, as shown in Figures 8, 9, 10 and 15.

Each of the rotors 21 and 22 have integral projections 67 and 68 extending from opposite sides thereof near the shoulder α defined by the swaged portions 33 and 34 thereof adjacent to the arrangements of teeth 27 and 28 formed thereon, as exemplified in Figures 5, 6, 9, 10, 11 and 12. Cams 69 and 70 are formed integrally of each side of each member 21 or 22 in transverse arrangement with respect to the lugs or projections 67 and 68. The cams 69 and 70 are formed near the rims or open ends of the rotors 21 and 22, as illustrated in Figures 5, 9 and 10, and spaced inwardly from the lugs 67 and 68.

Equidistantly spaced about the interior wall of the casing 10 are a plurality of integral bosses 71 which are formed with vertically arranged rectangular receptacles 72, each adapted to operatively receive a tensioned stop 73 which has horizontally projecting portions 74 and 75 formed on each end, as illustrated in Figures 5 and 6. Each member 73 has a pair of vertically spaced springs 76 therebehind tending to urge the same outwardly so that the upper projecting portion 74 is engaged by one of the lugs or projections 67 or 68, as illustrated in Figure 5, while the opposite member 75 is engaged by the oppositely arranged lugs on the opposite rotor, the cams 69 and 70 being engageable with the body portions of the stops 73 between the projecting portions 74 and 75 urging the same outwardly against the springs 76 to release the lug 67 or 68 permitting the rotor 21 or 22 to continue rotation.

In operation, the combined rotors 21 and 22,

operatively associated in the manner illustrated in Figures 1, 4 and 5, the intermittently and alternately rotated by the gear assembly previously described and shown in detail in Figures 2, 7 and 8. The members 21 and 22 are arranged, with respect to each other, so that the notches or recesses 31 dividing the arrangements of teeth 27 on the rotor 21 are aligned transversely with respect to the notches 42 and 43 in the teeth 28 of the member 22, as would be the case if the rotors 21 and 22 were assembled in the positions shown in Figures 11 and 12. It will be observed, by reference to these illustrations, that the notches 31-32 and 42-43 are spaced approximately intermediate the lugs 67 or 68 and the cams 69 or 70.

An example of the operation of the rotors 21 and 22, in their intermittent or alternate rotation, to function to pump liquids follows:

The uppermost rotor 21 is rotated by the gears 50 and 51 and the pinions 46 and 47, as by the arrangement shown in Figure 1, until the pinions 46 and 47 register with the notches or recesses 29 and 30 in the teeth 27 thereon, at which point in the rotation of the rotor the lugs 67 are engaged by the tensioned stops 73 opposite thereto by which the rotor 21 is arrested in its movement while the lower pinions engage the lower set of teeth 28 on the rotor 22 to rotate the latter one-half turn. The cams 70 on the member 22, meanwhile, engage the body of the stops 73 between the legs 74 or 75 to move the same outwardly to disengage the upper legs of the stops 73 from the lugs 67 on the upper rotor 21 so that it, in its turn, may be rotated as just described.

The vanes 25 in the upper rotor 21 move in the direction indicated by arrows in Figure 9 until these members contact the opposite vanes in the lower rotor 22 and maintains its said contacts for an instant until the opposite vanes 26 in the lower rotor 22 are moved past the ports or passages 19 in the shaft 15, or to the positions illustrated in Figure 10.

It must be borne in mind that the ports or passages through the shaft 15 comprise two inlet ports 19 and 19' and two discharge ports 20 and 20' for the intake and discharge of fluid into and from the chamber 41 within the rotors 21 and 22 and function, as apparent in Figures 9 and 10, to alternately admit and discharge fluids according to the alternate operation of the sets of vanes 25 and 26 in the rotor assembly.

In Figure 9 the vanes 27 are so arranged that the intake of fluids through ports 19 and 19' is about to occur as soon as the ports are cleared while discharge will occur through the ports 20 and 20'. The intake ports or passages 19 and 19' communicate with any suitable conduits connected to the coupling 17 attached to a boss 18 beneath the bottom 17 of the casing 10, as shown in Figure 1, while the discharge ports 20 and 20' communicate with the interior of the casing 10 through the boss 16 in the bottom of the casing 10, the fluids being discharged therefrom through an outlet conduit 79 threaded into the bottom 17 of the casing 10.

A cover 80 is provided for the gear assembly and is applied over the cover plate 12 and secured by screws 81, or the like, in the manner shown in Figure 5.

Manifestly, the structure herein shown and described is capable of certain changes and modifications by persons skilled in the art without departing from the spirit and intent of the invention or the scope of the appended claim.

What is claimed is:

In a pump mechanism for fluids having an outer casing and a stationary shaft arranged vertically therein and fluid inlet and outlet passages formed longitudinally of said shaft, in combination, a pair of cylindrically formed rotor members each having one of their ends closed, the said members being axially joined at their open ends and capable of independent rotation with respect to each other on the said shaft, a pair of axially arranged vanes formed in each of said rotors and extending beyond the open ends of said rotors so that said vanes on one of said rotors extend into the opposite of said rotors in interposed relationship with the opposite set of said vanes, gear segments formed about the closed ends of each of said rotors, the segments of one of said rotors being arranged axially opposite to the segments of the opposite rotor, cam and lug means for effecting the independent alternate intermittent arrest of said rotors, and a plurality of driven pinions operatively meshing with the gear segments of each of said rotors whereby the said rotors are alternately and intermittently rotated.

LESTER V. JONES.
